UNITED STATES PATENT OFFICE.

JOHN McRAE, OF VANCOUVER, BRITISH COLUMBIA, CANADA.

MARINE-ENGINE-OPERATION INDICATOR.

1,345,384.

Specification of Letters Patent. Patented July 6, 1920.

Application filed July 25, 1919. Serial No. 313,231.

To all whom it may concern:

Be it known that I, JOHN McRAE, a subject of the King of Great Britain, and a resident of the city of Vancouver, in the 5 Province of British Columbia, Canada, have invented certain new and useful Improvements in Marine-Engine-Operation Indicators, of which the following is a specification.

10 My invention relates to indicating devices associated with the operation of marine engines, and the object of my invention is to provide a simple device the use of which will prevent mistakes in such operation.

15 I attain this object by the construction illustrated in the accompanying drawings in which—

20 Figure 1 is a diagrammatic view illustrating the practical application of my invention.

Fig. 2 is a detail view of the indicator.

Similar figures of reference indicate similar parts throughout the views.

25 In operating marine engines it sometimes happens that the engineer instead of carrying out the order received from the bridge, will do exactly the opposite, that is instead of putting the engine full speed ahead, for instance, in response to the order for full 30 speed, he will put the engines full speed astern, or vice versa, with consequent damage if the vessel is being worked into dock, a lock, or any close space. The possibility of such such mistakes is readily understood 35 by those skilled in the art, as, while a transmitter is provided in the engine room for indicating the respective signals to the engineer which he has to operate after each signal so as to repeat the same back to the 40 bridge, it soon becomes a mere mechanical act on the part of the engineer to actuate the transmitter handle without paying such attention to the indicated signal as will impress it unmistakably on his brain, as in 45 most cases the transmitter is behind him so that he has to turn his back to it to move the engine operating levers to carry out the order.

50 In order to eliminate the possibility of such mistakes and to provide a sign, as it were, which will always be in view of the engineer when operating the reversing lever, I mount on the engine column 1 adjacent the handle 2 of the reversing lever 3 a rotatable 55 disk 4 provided with a pointer 5 from the

end of which depends a short chain 6 to the free end of which is preferably secured a point 7 in the shape of an arrow. Around the periphery of this disk 4, which is grooved, is passed an endless wire or chain 8 which also passes around a similar disk 9 mounted on the operating handle shaft 10 of the bridge transmitter 11 and the arrangement is such that when the bridge transmitter handle is at "Stop", that is, in 60 mid position, and also the reversing lever 3, the pointer 5 will be vertical, as shown in Fig. 1, but when the bridge transmitter handle is at "Full ahead" or "Full astern" as the case may be, the pointer 5 will be horizontally on either one side or the other of the vertical center line respectively, as indicated in Figs. 1 and 2, or referring to Fig. 1, the pointer is shown by the dotted lines lying horizontally on the inner side of the vertical 65 center line, having been moved thereto by the actuation of the bridge transmitter when moving the transmitter handle to "Full 70 astern", so that all the engineer has to do is to move the reversing lever over toward the 75 arrow point 7, which is then hanging down as indicated. Should the bridge transmitter be operated to signal "Full ahead" then the movement of the handle would operate the 80 wire 8 to rotate the disk 4 to carry the 85 pointer 5 over to lie horizontally on the outer side of the center line, when the engineer would then move the lever over toward this arrow point, which would then be in the 90 position indicated in Fig. 2.

It will thus be seen that an indicator is provided which is always in view of the engineer to indicate positively the direction in which to move the reversing lever to carry out a given signal and without depending 95 on the mind to carry the transmitter signal, so that mistakes in operation are thereby avoided.

What I claim as my invention is:

An indicator of the character described 100 comprising a rotatable body provided with a pointer normally vertical, a flexible element secured to the end of said pointer terminating in an indicator, and operating means for rotating said body to carry said 105 pointer to horizontal positions respectively on either side of its vertical center line.

Dated at Vancouver, B. C. this 4th day of July, 1919.

JOHN McRAE.
